UNITED STATES PATENT OFFICE.

EDWARD CULOTTA, OF RICHMOND HILL, NEW YORK.

SPOT TRIMMING FOR DRESSES.

Application filed February 18, 1922. Serial No. 537,614.

To all whom it may concern:

Be it known that I, EDWARD CULOTTA, a citizen of the United States, residing at Richmond Hill, in the county of Queens and 5 State of New York, have invented certain new and useful Improvements in Spot Trimmings for Dresses, of which the following is a full, clear, and exact specification.

This invention relates to trimmings for 10 ladies' dresses, and has for its object to provide an improved and simplified form of spot trimming.

Metallic spots are extensively used for 15 trimming, and have heretofore been made with dome shaped metal heads having spurs for fastening them to dress goods. The present invention contemplates making the heads of celluloid or other suitable plastic material, and mounting said heads on metallic 20 backing plates having spurs for connecting to the dress goods.

A special object of the present invention is to provide simplified means for securing 25 the plastic heads to the backing plates. Other objects will appear as the description proceeds.

The invention will be first hereinafter described in connection with the accompanying drawings, which constitute part of this 30 specification, and then more specifically defined in the claims at the end of the description.

In the accompanying drawings, wherein 35 similar reference characters are used to designate corresponding parts throughout the several views:—

Figure 1 is a plan view of a backing plate blank such as may be used in the manufacture of my improved spot trimming.

Figure 2 is an edge view of the same.

Figure 3 is a section thereof on the line III—III of Figure 1.

Figure 4 is a section of the backing plate after the plastic head has been attached 45 thereto and the attaching spurs have been bent down.

Figure 5 is a side elevation of the completed spot trimming.

Figure 6 is a side view of the spot attached 50 to a piece of dress goods, the latter being shown in section, and

Figure 7 is a plan view of a modified form of spot trimming hexagonal in form.

The metallic backing plate 1 is preferably 55 made round with an angular opening 2 therein and spurs 3 projecting from its edge.

Said spurs are bent down, as shown in Figure 4 for passing through the dress goods 4, Figure 6, on which they may be clinched, as at 5, for securing the spot trimming 60 thereto.

The head 6 of celluloid or other suitable plastic substance is molded on the backing plate 1 when warm and pliable, and in working the same to the desired shape for covering and fitting said plate, part of said substance passes through the opening 2 and is formed into a plate of flange 7 underlying the under surface of said backing plate, as shown in Figure 4. The plastic head is thus 70 securely fastened to the backing plate when the substance hardens, and the angular shape of the opening 2 serves to prevent said head from turning or twisting on said backing plate. Said opening 2 is preferably made 75 square, as shown in Figure 1, but other angular shapes may be employed.

The shape of the spots may be varied as suggested in Figure 7 where a hexagonal spot is shown. It is obvious that many other 80 shapes may also be made, such as diamonds, triangles, squares, rectangles, etc., as well as the round form shown in Figure 5. The heads may also be colored to suit different tastes and requirements.

I claim:

1. In a device of the character described, the combination with a backing plate having an opening therein, of a head of plastic material covering said plate and having an 90 integral portion extending through said opening and underlying said plate, and means for fastening said plate to dress goods.

2. In a device of the character described, 95 the combination with a backing plate having an opening therein, of a head of plastic material mounted on said plate and having an integral portion extending through said opening and underlying said plate for the 100 purpose specified.

3. In a device of the character described, the combination with a backing plate having an angular opening therein, of a head of plastic material mounted on said plate and 105 having an integral portion extending through and filling said opening, and an annular flange underlying said plate for the purpose specified.

In testimony whereof I have signed my 110 name to this specification.

EDWARD CULOTTA.
